UNITED STATES PATENT OFFICE

MAURICE SAMBURG, OF BROOKLYN, NEW YORK, ASSIGNOR TO LOCK PATENTS HOLDING CORPORATION, OF NEW YORK, N. Y., A CORPORATION OF NEW YORK

LOCK

Application filed January 12, 1929. Serial No. 332,089.

This invention relates to locks. More particularly it is directed to a latch lock for brief cases, trunks, and the like.

An object of this invention is to provide a device of the character described having means for positively ensuring movement of the latch away from the locking mechanism upon release of said latch.

A further object of this invention is to provide a neat, compact and rugged device of the character described which shall comprise few and simple parts, which shall be positive in operation, relatively inexpensive of manufacture and yet practical and efficient to a high degree in use.

Other objects of this invention, will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention.

Fig. 1 is a front view of a lock embodying the invention applied to a brief case;

Fig. 2 is a cross-sectional view taken on line 2—2 of Fig. 1;

Fig. 3 is a cross-sectional view taken on line 3—3 of Fig. 1;

Fig. 4 is a rear view of the lock removed from the brief case, with parts broken away to disclose the interior construction;

Fig. 5 is a front view similar to Fig. 4 with the parts in latch releasing position;

Fig. 6 is a cross-sectional view taken on line 6—6 of Fig. 5.

Referring in detail to the drawings, 10 designates a portion of the body of a brief case, bag or other like article having a flexible flap cover 11. Said flap 11 is provided with hasp 12 having a latch bolt or stud 13 adapted to coact with mechanism 14 mounted on the body 10 for locking and unlocking said flap cover.

Said hasp 12, as here shown, comprises a metallic plate 15 folded over on itself to provide a front wall 16 and rear wall 17 engaging opposite faces respectively of an edge portion 18 of said flap 11. A pronged extension 19 integral with said rear wall 17, pierces the flap portion 18, extends thru an opening 20 in front wall 16, and is then bent back to tightly clamp the walls 16, 17 to said flap. Riveted to the rear wall 17 as at 21 and extending outwardly therefrom is the latch bolt or stud 13. Said stud is slotted or grooved as at 22 to provide a hook portion 23, and is further formed with oppositely inclined cammed surfaces 24, and 25. Extending at right angles to the hook portions 23 is a wall 26 providing an abutment surface 27 for a purpose hereinafter appearing.

The locking and releasing mechanism 14 with which the stud 13 cooperates, comprises a casing 30 having a front wall 31 and a skirted wall 32 extending rearwardly therefrom and having edge contact with said body portion 10. For attaching said casing to said body 10, a plate 33, positioned within said casing 30, is provided with bent arms 34 riveted as at 35 to the front wall 31. Said plate 33 is spaced from said front wall 31 to provide an intervening chamber 36. Extending rearwardly from said plate 33 are a plurality of pairs of aligned prongs 37 extending thru said body portion 19 and bent inwardly as at 38 to firmly secure the plate and casing to said body portion.

Said plate 33 and front face 31 of casing 30 are formed with a plurality of aligned similar slots 39, 39' respectively for receiving the latch stud 13. Said slots are preferably L shaped, having a portion 40 for receiving the hook portion 23, and a portion 41 for receiving the wall 26 of said stud, said latter portion 41, presenting an edge 42 adapted to abut surface 27 of said wall 26. Pivottally mounted on a pin 44 fixed to front wall 31 and plate 33, and housed within chamber 36, is a locking and releasing plate member 45. A wire spring 46 secured to said member 45 at one end and engaging a lug 47 integral with plate 33 at its opposite end, normally maintains said member in locking

position, as illustrated in Figs. 3 and 4. For actuating said member to releasing position against the pressure of said spring 46, a shaft 48 is rotatably mounted on front face 31 of said casing 30, adjacent the pin 44, and is formed with an enlarged portion 49 extending within said chamber 36. Plate 33 and member 45 are provided with cut away portions 50 and 51 respectively for receiving said enlarged portion. The cut away portion 51 in the locking member 45 presents a cammed edge 52 adapted to coact with a pin 54 extending from said portion 49. A knob 55 secured to the outer end of said shaft provides an actuating handle for rotating said shaft 48 to cause pivotal movement of member 45 against the pressure of said spring 46.

Said member 45 is formed with a substantially oblong longitudinal slot 56, providing a pair of opposite edge portions 57 and 58. Said edge portions are bevelled or cammed as at 57' and 58' respectively, on the face of said member 45 adjacent wall 31 of the casing, for a purpose hereinafter appearing. The width of the slot 56, or the distance between the edges 57 and 58 is substantially equal to the width of the stud 13 to permit the latter to pass thru said slot during the locking and releasing operations.

The operation of the device will now be apparent. To lock the brief case, the flap 11, and the attached hasp 12 is moved to a proper position for aligning the stud latch 13 with any one of the slots 39, depending on the adjustment desired. The hasp may then be pushed against the casing 30 to force the stud latch thru the aligned slots 39, 39', the cammed surface 24 of said stud coacting with the cammed surface 57' of the edge portion 57 during this operation, to rotate the member 45 about pin 44 against the pressure of spring 46. Once the hook portion 23 of the stud is past the edge 57, member 45 snaps back into normal position, said edge 57 entering slot 22 for preventing removal of said stud and retaining the flap 11 in closed condition. This position is illustrated in Figs. 2, 3, and 4.

Any suitable means such as combination controlled mechanism (not shown) may be provided for preventing actuation of the knob 55 to unlocking position. When such mechanism is not provided, to unlock the flap 11, it is merely necessary to rotate the knob 55 to the position shown in Fig. 5. During this operation, member 45 is rotated clockwise (looking at Fig. 5), or to the right (looking at Fig. 6), edge portion 57 moving out of groove 22 to release the hook 23. When said edge 57 has moved out of said slot 22, to disengage said hook 23, the opposite cammed edge portion 58 strikes the cammed surface 25 and forces the stud latch 13 outwardly to the position shown in Fig. 6.

Thus, not only is the latch released but the entire hasp and therefore the flap 11 are moved outwardly to open position, and subsequent release of the knob 55 will not again lock the device since the stud is entirely removed from the locking mechanism. It will be noted that during the unlocking operation, wall 26 of said stud abuts the edge 42 of slot 39 and said stud being thereby guided directly outwardly without danger of the hook 23 catching the under surface of the casing wall 31.

Although the drawings show the lock applied to a brief case, or the like, it will be understood that the hasp 12 may be pivoted to a trunk cover or that of any other article applied to any other suitable closure member.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention I claim as new and desire to secure by Letters Patent:

1. In a lock, in combination, a latch bolt, means for engaging said bolt to retain the same in locked condition, means for actuating said engaging means to release said bolt, and means associated with said engaging means for moving the bolt out of locked position.

2. In a lock, in combination with a hasp having a latch bolt, a slotted member for receiving said bolt, means for engaging said bolt to retain the same in locked condition, means for actuating said engaging means to release said bolt, and means associated with said engaging means, for forcing said bolt outwardly from said slotted member.

3. In a lock, in combination with a hasp having a latch bolt, a casing having a slot for receiving said bolt, means for engaging said bolt to retain the same in locked condition, means for actuating said engaging means to release said bolt, and means associated with said engaging means, for forcing said bolt outwardly with respect to said casing slot.

4. In a lock, in combination with a hasp having a latch bolt, a casing having an opening for receiving said bolt, keeper means for said latch to prevent removal thereof from said casing and means for successively releasing said bolt and ejecting the same out of said opening.

5. In a lock, in combination with a hasp having a latch bolt, a casing having an open-

ing for receiving said bolt, means for inter-engaging said bolt to prevent removal thereof from said casing, means for successively releasing said bolt and ejecting the same out 5 of said opening, and means associated with said bolt and casing for guiding said bolt during movement thereof out of said opening.

6. In a lock, in combination with a hasp 10 having a latch bolt, a casing having an opening for receiving said bolt, means for inter-engaging said bolt to prevent removal thereof from said casing, means for successively releasing said bolt and ejecting the same out 15 of said opening, said interengaging means comprising a member movably mounted within said casing, and having an opening for receiving said bolt.

7. In a lock, in combination with a hasp 20 having a latch bolt, a casing having an opening for receiving said bolt, means for inter-engaging said bolt to prevent removal thereof from said casing, said means comprising a member movable within said casing and 25 having an opening for receiving said bolt, said member being provided with a cammed portion adapted to coact with said bolt to eject the latter from said casing.

8. In a lock, in combination with a hasp 30 having a latch bolt, a casing having an opening for receiving said bolt, means for inter-engaging said bolt to prevent removal thereof from said casing, and means for successively releasing said bolt and ejecting the 35 same out of said opening, said bolt having a surface adapted to abut an edge of said casing at said opening during said ejecting operation.

9. In a lock, in combination with a stud 40 having a hook portion, a member having an opening to receive said stud, and a plate movable relative to said member, said plate having a pair of edge portions, one of said portions being adapted to engage said hook 45 portion to prevent removal of said stud from said member, said other edge portion having a portion adapted to coact with said stud to eject the latter from said opening upon movement of said plate.

50 10. In a lock, in combination with a stud having a hook portion, a member having an opening to receive said stud, and a plate movable relative to said member, said plate being provided with a pair of edge portion, 55 one of said portions being adapted to engage said hook portion to prevent removal of said stud from said member, said other edge portion having a portion adapted to coact with said stud to eject the latter from said opening upon movement of said plate, said stud having a surface adapted to contact an edge portion of said member during said ejecting movement.

60 In testimony whereof I affix my signature.
65 MAURICE SAMBURG.
